4 Sheets-Sheet 2

This technical cross-sectional diagram illustrates a complex mechanical assembly, possibly a pump or compressor, featuring a vertical arrangement of various components. The diagram is labeled with numerous part numbers, including:

- 45, 42, 43, 44, 34, 35, 36, 37, 40, 73, 60, 62, 66, 74, 71, 72, 82, 91, 93, 58, 57, 48, 41, 46, 29, 30, 33, 31, 18, 25, 28, 19, 25, 30, 33, 70, 28, 29, 15, 32, 20, 25, 21, 25, 28, 29, 17, 77, 80, 22, 23, 77, 78, 79, 14, 89, 87, 86, 10, 27, 26, 49, 50, 51, 52, 53, 81, 13, 67, 68, 69, 54, 55, 81, 88, 90.

The diagram shows a central vertical axis with various ports, valves, and internal mechanisms. A large cylindrical component on the right is labeled with part numbers 57, 54, 67, 68, 69, 14, 89, 87, 86, and 10. The bottom section features a base with a central opening and side ports labeled 79 and 78. Numerous lines and hoses connect the different parts, forming a complex network. The top of the diagram features a label "FIG-2." with a small number "4" below it.

FLASHER

George H. Leland, Dayton, Ohio, assignor of
one-half to The Leland Electric Company,
Dayton, Ohio, a corporation of Ohio

Application March 31, 1930. Serial No. 440,379

16 Claims. (Cl. 200—32)

This invention relates to flashers such as are used to control the operation of electric signs and the like, and more particularly to a flasher employing mercury tube switches.

5 One object of the invention is to provide a flasher of such a character that the switches will be operated in accurately timed relation and will break and close the circuits quickly.

A further object of the invention is to provide 10 a flasher of such a construction that the number of switches embodied therein and the timing of these switches may be readily varied.

A further object of the invention is to provide 15 a flasher which will be simple in its construction, compact in its arrangement and may be manufactured and assembled at a low cost.

Other objects of the invention will appear as the apparatus is described in detail.

In the accompanying drawings Fig. 1 is a front 20 elevation of a flasher embodying my invention, with the casing omitted; Fig. 2 is a side elevation of the flasher mechanism, partly in section; Fig. 3 is a section taken on the line 3—3 of Fig. 1; Fig. 4 is a section taken on the line 4—4 of Fig. 2, 25 looking in the direction of the arrows; Fig. 5 embodies detail views of the several controlling cams; and Fig. 6 is a diagram illustrating the timing of the switches.

In these drawings I have illustrated one embodiment of my invention and have shown the same as applied to a flasher designed to control an electric sign in which the letters of the sign word are successively illuminated to spell the word and which is provided with a traveling border. It 30 will be understood, however, that this particular embodiment has been chosen for the purposes of illustration only, that the mechanism may take various forms and may be utilized for controlling signs or other devices of various kinds.

40 In that embodiment of the invention here illustrated the mechanism is carried by a single frame which is shown in the form of a plate comprising a lower vertical portion 10, and an upper vertical portion 11 offset forwardly from the lower portion 45 and connected thereto by an inclined transverse portion 13. The frame may be mounted in any suitable manner but it is preferably arranged within a casing 14, which encloses the mechanism, and it is here shown as mounted on the rear wall 50 of the casing. The casing has a removable front wall 15 to permit access to be had to the flasher. The transverse portion 13 of the frame has an opening 16 therethrough and the upper portion 11 of the frame has a part 17 depending therefrom below the transverse portion 13.

The switches which control the circuits are of the mercury type but it will, of course, be obvious that any suitable conducting material may be used within the tubes and the term "mercury tube" is herein employed to indicate the character of the switch and not the specific construction thereof or the material used therein. The present flasher is adapted to control a sign comprising a word of four letters and having a border of lamps which are so controlled as to impart to the border the appearance of traveling about the sign. The circuits for the respective letters of the sign word are so controlled as to cause the letters to be successively illuminated to spell the word, to then darken all the letters, then simultaneously illuminate all the letters, then again darken them and subsequently repeat the cycle of operations. For this purpose I have provided four mercury tubes 18, 19, 20 and 21. The traveling border is controlled by two double contact mercury tubes 22 and 23 forming part of a border controlling device which is commonly termed a "border chaser". Numerous types of mercury tubes are known in the art and any suitable type of tube may be employed, those here shown having been chosen because they were best adapted to the needs of the present flasher.

The mercury tubes for controlling the letter circuits each comprises an elongated body portion having near one end a pocket or well 24 and having a second pocket or well 25 spaced a short distance from the pocket or well 24. The tube contains mercury in sufficient quantity to fill both wells and to bridge the space between the two wells when the tube is in one position, but the quantity of mercury in the body of the tube is such that when the tube is tilted to another position the mercury in the body of the tube will move out of contact with the mercury in the well 24 and thus break the circuit. Each of the wells 24 has mounted therein an electrode and these electrodes are connected with flexible conductors 26 which lead to a distributing panel 27 through which the flexible conductors are connected with the respective letter circuits. Each of the mercury tubes 18, 19, 20 and 21, is supported by a clip 28 which is carried by and forms a part of a tube supporting device or bracket 29 which is pivotally mounted for movement about an axis transverse to the length of the tube. Connected with and extending upwardly from each tube supporting device 29 is a trip arm 30 by means of which the supporting device may be rocked about its axis to tilt the tube in one direction or the other. For the sake of compactness the four

letter controlling tubes are arranged in pairs, one pair being mounted below the other and the tubes of the two pairs being arranged in different vertical planes. In the construction 5 here shown the tube supporting devices for the upper pair of tubes, 18 and 19, are pivotally mounted on a stud 31 which is carried by and extends forwardly from the upper portion 11 of the main frame. The supporting devices 29 10 for the tubes of the lower pair, 20 and 21, are mounted on a stud 32 carried by and extending forwardly from the depending portion 17 of the frame. Connecting arms or levers 33 are pivotally mounted on the upper stud 31 and have their 15 lower ends bifurcated to embrace the upper ends of the trip arms 30 of the lower tube supporting devices and in effect constitute extensions of the trip arms of the lower tube supporting devices. By means of this arrangement of the tubes they 20 can be placed close together and the construction of the flasher rendered very compact. The connecting levers which are mounted on the upper stud occupy much less space than would be occupied by tube supporting devices. It will be 25 obvious that by varying the length of the supporting studs the number of tube supporting devices may be varied and thus the circuit capacity of the flasher increased or decreased.

The several letter controlling tubes are actuated by mechanism comprising parts arranged 30 to act on the respective tube supporting devices to move the same in one direction, to then release the tube supporting device and subsequently return it to its initial position. Preferably the actuating mechanism for each tube supporting device comprises two pivoted members arranged to 35 act on the respective sides of the trip arms 30, either directly or through the connecting arms 33, and these actuating members are so controlled 40 that one member will first act upon the tube supporting device to move it from its initial position, will then be retracted and subsequently the other actuating member will act on the tube supporting device to return it to its initial position. The 45 mechanism may take various forms and may be controlled in various ways but, in the present instance, it is cam controlled and a separate controlling cam is provided for each tube, these cams being indicated as a whole by the reference numerals 34, 35, 36 and 37 (Fig. 5). The several 50 cams are, in the form here shown, rigidly secured to a tubular shaft or sleeve 38 which is rotatably mounted upon a stud 39 carried by and extending forwardly from the part 11 of the supporting frame. The several cams are keyed to the sleeve, are spaced one from the other by collars 40 and are held against axial movement by a nut 41 on the forward end of the sleeve. The actuating members for the tube supporting devices are arranged on opposite sides of the respective cams. 55 As here shown, the actuating device for each tube supporting device comprises two arms 42 and 43 which are pivotally mounted at their upper ends on studs 44 carried by the part 11 of the frame and spaced some distance above the cam shaft. Each arm has its lower end curved inwardly so as to lie beneath its cam. The two arms are acted upon by a bow spring 45, the curved ends of which are seated in recesses 46 in the outer edges 60 of the respective arms. Each arm has on its inner edge an inwardly extending projection or tooth 47 and the spring 45 presses the teeth of the two arms against the cam so that the position of the arms will be controlled at all times by the rotation of the cam. Each cam is provided with

two circumferential series of recesses to receive the teeth 47 of the respective arms and preferably each cam consists of two disks rigidly connected one to the other, the two series of recesses being formed in the respective disks. In the drawings I have indicated the two disks of each cam by the letters *a* and *b*, the letter "*a*" representing that part of the cam which controls the actuating member that serves to move the mercury tube switch to its closed position, and the letter "*b*" representing that part of the cam which controls the actuating member which moves the switch to its open position. The several cams rotate in unison in the same direction and because of the interposition of the connecting levers 33 between the lower mercury tubes 20 and 21 and their actuating devices the positions of the parts of the cams for these tubes are reversed with relation to the other cams, that is to say, in the cams 34 and 36, which control the upper pair of mercury tubes 18 and 19, the part *a* or "on disk" is arranged in front of the part *b* or "off disk", while in the cams 35 and 37 for the lower tubes 20 and 21 the disk *b* is in front of the disk *a*. Likewise the actuating members 42 or 100 "on arms" which move the tubes 20 and 21 to their closed positions, are on that side of the cam shaft opposite the arms which move the tubes 18 and 19 to their closed positions. Thus all the tubes are moved in the same direction to their 105 closed positions or to their open positions by the action of the cams rotating in the same direction. If desired, a spacing disk 48 may be interposed between the two disks of each cam and project a short distance beyond the peripheries of those 110 disks to prevent the lateral displacement of the respective actuating arms and so hold the arms in proper relation to their respective disks. The part *a* of each cam has a peripheral notch 49 to receive the tooth of the "on arm" 42 and permit that arm to be moved by the spring 45 into engagement with the trip arm or connecting arm, as the case may be, and thus move the corresponding mercury tube to its closed position. In Fig. 5 I have shown the several cams in the positions which they occupy when the "on arm" 34 is in a position to cause the mercury tube 18 to close the circuit through the first letter of the sign word. The recesses 49 in the parts *a* of the cams 35, 36 and 37, are so arranged with 120 relation to the recesses 49 in the part *a* of the cam 34 that the continued movement of the several cams in the same direction will cause the corresponding mercury tubes, 20, 19, and 21, to be moved to their closed positions one after the 125 other, thus causing the letters of the sign word to be successively illuminated. In the present arrangement this requires approximately a quarter rotation of the cam shaft. The mercury tubes will be held in the positions to which they 130 have been moved by the weight of the mercury therein but, if desired, a slight friction may be imposed upon the tube supporting devices to prevent the vibration of the tubes after their movement has been completed in either direction. As here 135 shown, washers 31a are arranged between the adjacent parts on the stud 31 and are keyed to the stud. The tightening of the screw on the end of the stud presses the washers into firm engagement with the tube supporting devices and the 140 levers adjacent to which they are mounted and exerts sufficient friction on those parts to retain the tubes in the positions to which they are moved. The arrangement is such that the desired friction will be imposed on each tube sup- 150

porting device and tube operating lever without any tendency to frictionally connect the several parts one to the other. As soon as one tube has been moved to its closed position the continued movement of the cam will cause the actuating arm 42 to be withdrawn out of the path of the trip arm, and after all the tubes have been moved to their closed positions they will remain in those positions for a further interval of time which, in the present arrangement, equals approximately a quarter rotation of the cam shaft. At the end of this interval the recesses 50 in the parts *b* of the several cams will be brought into line with the teeth of the respective "off arms" 43 and these arms will act simultaneously to tilt the several mercury tubes in the opposite direction and thus break the circuits through the same. The circuits remain broken for a brief interval, at the end of which the recesses 51 in the parts *a* of the several cams are brought into line with the teeth of the respective "on arms" 42, thereby causing all of the tubes to be tilted simultaneously to their closed positions and instantaneously illuminating all the letters of the sign word. After a further interval, during which all the sign letters are illuminated, the recesses 52 in the parts *b* of the cam are brought into line with the teeth of the respective "off arms" 43, thereby again causing the several tubes to be simultaneously moved to positions to open the respective circuits. After a brief interval the recess 49 of the part *a* of the cam 34 is again brought into a position to move the tube 18 to its closed position and the cycle of operations is repeated.

As will be apparent from the foregoing description the actuating mechanism is of such a character that each switch or mercury tube will be moved quickly into and out of its circuit closing position. When the nose of an actuating member 43 enters a recess in its cam, under the influence of the spring 45, the tube supporting device with which that lever is associated will be quickly moved in a direction to move the tube to its circuit opening or inclined position. The continued movement of the cam will retract the actuating member against the action of the spring 45, thereby expanding that spring and storing energy therein. The tube will remain in the position to which it has been moved until the nose of the other actuating member, 42, enters a recess in the cam and thereby causes the tube to be quickly moved to its initial or circuit closing position. The forward edges of the recesses in the cam are preferably slightly inclined to the radius of the cam so that the nose of the actuating member will slide down these inclined surfaces and will gently engage the bottom of the recess, thus avoiding the noise and shock which would result if the nose of the actuating member dropped abruptly into the recess. However, the inclination of the forward edge of the recess is so slight that it will not appreciably retard the movement of the actuating member.

The several cams which control the actuating devices for the mercury tubes above described are driven from a suitable motor, which is preferably an induction motor and is, in the present instance, mounted in the space between the upper part 11 of the supporting frame and the rear wall of the casing or cabinet which encloses the mechanism. Obviously the motor may take various forms but, as here shown, it comprises a disk 53 carried by a shaft 54 and arranged between the poles of two magnets 55 and 56 each of which is provided with a shading coil 57. The respective magnets are pivotally mounted on the frame by studs 58 and 59 and are held in adjusted positions thereon by means of screws 60 which extend through slots 61 in the frame and are threaded into arms 62 rigidly connected with the magnets. By thus adjusting the magnets about their axes the poles thereof can be caused to overlap the disk 53 to a greater or lesser extent and the speed of the motor thereby varied. The motor shaft 54 may be mounted in any suitable manner but, as here shown, it is arranged in line with the upper stud 31 which carries the tube supporting devices 29 for the upper pair of mercury tubes. This stud is supported by the forward end of a fitting or block 63 which is rigidly secured to the part 11 of the frame and which has a longitudinal bore 64 and a circumferential opening 65 in the upper side thereof. The end of the stud 31 is recessed to receive a ball bearing 66 and the end of the shaft 54 extends into the bore 64 of the fitting 63 and has its end tapered to engage the bearing 66 in the end of the stud. The other end of the shaft 54 is also pointed and engages a ball bearing 67 formed in the inner end of a stud 68 supported in line with the stud 31. Preferably the bearing stud 68 is resiliently supported so that it will exert axial pressure on the shaft and cause the same to firmly engage its bearings. As here shown, the bearing stud 68 is mounted in the upper end of a resilient plate 69 which is rigidly mounted at its lower end on the part 10 of the frame. A pinion 70 is secured to the shaft 54, within the bore 64, and meshes with an idle gear 71 with which is connected an idle pinion 72 which meshes with a gear 73 rigidly secured to the cam shaft 38, thus causing the cam shaft to be rotated from the motor shaft at a greatly reduced speed. Preferably a fly wheel 74 is secured to the motor shaft to assist in carrying the motor across its peak loads, as when all of the mercury tube switches are to be shifted simultaneously.

The border chaser, including the mercury tube switches 22 and 23, comprises the subject matter of a separate application for patent (filed by me March 31, 1930, Serial No. 440,380) and forms a part of the present invention only in so far as it enters into combination therewith either in operation or in the assembling of the mechanism. In the traveling borders for signs the several lamps are usually arranged in groups of, say, four lamps each and the corresponding lamps of each group are controlled by a single switch, the several switches being so timed that the corresponding lamps of the several groups will be darkened simultaneously and the several lamps of each group will be darkened successively, thus imparting to the border the appearance of longitudinal movement. In the present apparatus the four circuits for the border are controlled by two mercury tube switches each of which is of such a character as to control two circuits. As here shown, each of these mercury tubes, 22 and 23, is curved and is so supported that its central portion will be the lowest portion of the tube. It is provided near its ends with mercury contact wells 75 and 76 which are connected with separate circuits, and has at its central portion a mercury contact well 77 which is connected with a conductor which is common to both circuits, the several contact wells being connected by flexible conductors 78 with the distributing panel 79 through which they are connected with the respective circuits. When the mercury tube is tilted in a direction to lower the well 76 the mercury

in the body of the tube will bridge the wells 76 and 77 and close the one circuit. When the tube is tilted in the opposite direction the mercury in the body of the tube will move out of contact 5 with the mercury in the well 76 and will bridge the wells 75 and 77, thus breaking the first circuit and closing the second circuit. Each mercury tube, 22 and 23, is mounted in clips 80 which are rigidly secured to the lower end of an actuating 10 arm 81 which is pivotally supported at a distance remote from the mercury tube, there being a separate arm 81 for each tube. In the present instance, the two arms 81 are pivotally mounted on a stud 82 carried by the part 11 of the frame 15 and extending rearwardly above the motor disk 53. Each arm has an opening 83 through which extends the motor shaft 54 and the longitudinal edges of this opening are provided with contact plates 84 with which engage a cam or eccentric 20 disk 85 rigidly secured to the motor shaft. Thus the rotation of the motor shaft will impart a very rapid oscillatory movement to the mercury tube, and cause the circuits to be opened and closed at very short intervals. The eccentric disks 85 are 25 so arranged with relation one to the other that the circuits will be closed in proper timed relation. It will be noted that while the actuating arms for the mercury tubes are directly driven from the motor shaft the tubes themselves are 30 supported below the transverse portion 13 of the frame and on the forward side of the part 10 thereof so that they are readily accessible from the front of the cabinet. The opening 16 in the transverse portion of the frame, through which 35 the actuating arms 81 extend, provides ample space for the oscillatory movement thereof.

The supporting frame 10—11 may be mounted on the housing or other supporting structure in any suitable manner but I prefer to provide the 40 same with a plurality of key hole slots 86 and to mount on the housing studs to enter these key hole slots and support the frame. The lower pair of studs, shown at 87, are provided at their outer ends with heads 88 of a diameter which will 45 permit them to pass through the larger portions of the key hole slots but which will overlap the narrow portions of the slots when lengthwise movement is imparted to the frame. Movable 50 mounted on each stud 87 is a yieldable member 89 which is here shown as cup-shaped and which is pressed outwardly by a spring 90. These yieldable members are of a diameter greater than the diameter of the larger portions of the key hole slots and act upon the adjacent surface of the 55 frame to press the same into firm engagement with the head of the stud. The upper stud 91 also has a head 92 to extend through the key hole slot and overlap the narrow portion thereof and is provided with a yieldable member 93 to 60 press the frame outwardly against the head. The head 92 of this stud is provided with an upwardly extending finger having a downturned end portion 94 of such length that when the frame is pressed outwardly against the head the edge of 65 the frame will engage the downturned portion or lip 94 of the head, which will hold the frame against lengthwise movement. When the frame is pressed rearwardly against the action of the yieldable member it will be moved out of line 70 with the lip 94 so that it may be moved lengthwise to disengage the same from the studs. In this manner the frame is firmly supported on the housing but there is no tendency to distort or twist the frame. It has been found that when 75 the frame is secured to the housing by screws the

frame may be so distorted, by the unequal tightening of the screws or the improper placing thereof, as to throw the motor disk out of line. This is entirely avoided by the mounting here illustrated.

While I have shown and described one embodiment of my invention I wish it to be understood that I do not desire to be limited to the details thereof as various modifications may occur to a person skilled in the art.

Having now fully described my invention, what I claim as new and desire to secure by Letters Patent, is:

1. In a mechanism of the character described, a pivoted tube supporting device, an arm connected with said supporting device, a pair of pivoted actuating members having parts arranged on the respective sides of said arm, resilient means to move said members one toward the other, and a cam comprising two disks rigidly connected one to the other and arranged to engage the respective actuating members and move the same against the action of said resilient means, and a separating disk arranged between the first mentioned disks and extending beyond the peripheries thereof to retain said actuating members in engagement with their respective disks.

2. In a mechanism of the character described, a plurality of pivoted tube supporting devices, arms connected with the respective supporting devices, spring pressed actuating members associated with the respective arms and so arranged that one actuating member will move said arm in one direction and the other actuating member will move said arm in the other direction, a cam arranged between each pair of arms, said cams being so shaped as to cause the actuating devices for the several tube supporting devices to move said tube supporting devices in a predetermined relation one to the other.

3. In a mechanism of the character described, a series of tube supporting devices pivotally mounted on a common axis, a second series of tube supporting devices pivotally mounted on a common axis below said first mentioned tube supporting devices, the last mentioned tube supporting devices being arranged out of line with the first mentioned tube supporting devices, connecting arms pivotally mounted on an axis coincident with the axis of the first mentioned tube supporting devices, and connected with the last mentioned tube supporting devices, an actuating mechanism arranged above the first mentioned tube supporting devices to act thereon and on said connecting arms to cause several tube supporting devices to be actuated in timed relation one to the other.

4. In a mechanism of the character described, a frame, a stud extending laterally from said frame, a plurality of tube supporting devices pivotally mounted on said stud, a cam shaft carried by said frame, extending parallel with said stud, cams carried by said shaft, actuating members controlled by said cams to actuate the respective tube supporting devices, a second stud extending laterally from said frame below the first mentioned stud, a plurality of tube supporting devices pivotally mounted on said second stud, arms pivotally mounted on the first mentioned stud and connected with the last mentioned tube supporting devices, actuating members controlled by the respective cams on said cam shaft for actuating said connecting arms, and means for actuating said cam shaft.

5. In a mechanism of the character described, a supporting frame having upper and lower portions offset one from the other and connected by a transverse portion, tube supporting devices 5 pivotally mounted on one side of the upper portion of said frame actuating mechanism for said tube supporting devices mounted on said side of said frame and operatively connected with said tube supporting devices, a motor mounted on that 10 side of said frame opposite said tube supporting devices and above said transverse portion, and means for operatively connecting said motor with said actuating mechanism. 80
6. In a mechanism of the character described, 15 a supporting frame having upper and lower portions offset one from the other and connected by a transverse portion, tube supporting devices pivotally mounted on one side of the upper portion of said frame, actuating mechanism for said tube supporting devices mounted on said side of said frame and operatively connected with said tube supporting devices, a motor mounted on that side of said frame opposite said tube supporting devices and above the transverse portion 20 of said frame and comprising a shaft, a bearing supported by said frame to receive one end of said shaft, a resilient member supported by said frame, a second bearing carried by said resilient member and spaced from the first mentioned bearing to 25 receive the other end of said shaft, and means for connecting said shaft with said actuating mechanism. 85
7. In a mechanism of the character described, a supporting frame having upper and lower vertical portions offset one from the other and connected by a transverse portion having an opening therethrough, a plurality of tube supporting devices mounted on one side of the upper portion of said frame, actuating mechanism mounted on 30 said side of said upper portion of said frame, means for operatively connecting said actuating mechanism with said tube supporting devices to cause the latter to be actuated in a predetermined relation one to the other, a motor on the 35 upper portion of said frame on that side thereof opposite said tube supporting devices, a pair of arms pivotally mounted on the last mentioned side of the upper portion of said frame and extending through the opening in the transverse 40 portion of said frame, tube supporting devices carried by said arms below said transverse portion of said frame, means actuated by said motor to rapidly oscillate said arms, and means for operatively connecting said motor with the actuating 45 mechanism for the first mentioned tube supporting devices. 100
8. In a mechanism of the character described a pivoted tube supporting device, an arm connected with said supporting device, a pair of pivoted actuating members having parts arranged on the respective sides of said arm, resilient means to move said members one toward the other, and a cam mounted between said actuating members and having two rigidly connected 50 parts arranged in parallel planes and having constant engagement with the respective members to retract the same and to release the respective members alternately and at predetermined intervals for movement by said resilient means. 105
9. In a mechanism of the character described, a plurality of pivoted tube supporting devices, each supporting device having a single trip arm, a pair of spring pressed actuating members associated with each trip arm and so arranged that 55 one actuating member will move said trip arm in one direction and the other actuating member will move said trip arm in the other direction, separate controlling devices acting on the actuating devices of the respective pairs of actuating devices to hold the same normally in their retracted positions and to release the same separately and at predetermined intervals, said controlling devices being so arranged with relation to one to the other that they will release the actuating devices for the several tube supporting devices in a predetermined sequence, and means for operating said controlling devices in timed relation one to the other. 110
10. In a mechanism of the character described, two series of tube supporting devices each having a trip arm, the supporting devices of each series being pivotally mounted on a common axis and the axis for the tube supporting devices of one series being arranged below the axis for the tube supporting devices of the other series, actuating mechanism acting directly on the trip arms of the upper series of tube supporting devices, and intermediate devices for operatively connecting said actuating mechanism with the trip arms of the tube supporting devices of the lower series. 115
11. In a mechanism of the character described, an upright supporting frame, tube supporting devices pivotally mounted on one side of said frame, actuating mechanism for said tube supporting devices mounted on said side of said frame and operatively connected with said tube supporting devices, a driving shaft supported at one end on the upper portion of said frame and extending beyond that side thereof opposite said tube supporting devices, means mounted on the last mentioned side of said frame for rotating said shaft, and gearing connecting said shaft with said actuating mechanism. 120
12. In a mechanism of the character described, a supporting frame having upper and lower portions offset one from the other and connected by a transverse portion, tube supporting devices pivotally mounted on one side of the upper portion of said frame, actuating mechanism for said tube supporting devices mounted on said side of said frame and operatively connected with said tube supporting devices, other tube supporting devices arranged below the transverse portion of said frame, actuating members connected with the last mentioned tube supporting devices and 125 pivotally supported in the upper portion of said frame on an axis above and remote from said transverse portion, driving mechanism mounted on that side of said frame opposite the first mentioned tube supporting devices and above said 130 transverse portion of said frame for imparting oscillatory movement to the last mentioned actuating members, and means for operatively connecting said driving mechanism with the actuating mechanism for the first mentioned tube supporting devices. 135
13. In a mechanism of the character described, a pivoted support for a mercury tube switch having an arm for tilting the same, an actuating member having a part arranged normally in such close relation to said arm that it may actuate the same without substantial impact, a spring tending to move said member in a direction to actuate said arm, a cam acting on said member to retain the same normally in its retracted position, to release the same for operation by said spring at predetermined intervals and to retract the same after each operation, and means to restore said arm to its normal position after said actuating member has been retracted. 140
14. In a mechanism of the character described, a plurality of pivoted tube supporting devices, each supporting device having a single trip arm, a pair of spring pressed actuating members associated with each trip arm and so arranged that one actuating member will move said trip arm in 145

14. In a mechanism of the character described, a pivoted support for a mercury tube switch having an arm for tilting the same, a pair of separately operable actuating members having parts so arranged on the respective sides of said arm that when said switch is at either limit of its movement one or the other of said parts will be closely adjacent to said arm, spring means for moving said actuating members one toward 10 the other, and a cam arranged between said actuating members and having means for releasing that actuating member which is adjacent to said arm to cause said arm to be moved to a position adjacent to the other actuating member, 15 for withdrawing the first mentioned actuating member, releasing said other actuating member to cause said arm to be restored to its initial position and to then withdraw the last mentioned actuating member.
16. In a mechanism of the character described, a pivoted support for a mercury tube switch having a trip arm to tilt the same, a cam mounted adjacent to said trip arm, actuating members pivotally mounted beyond that edge of said cam 20 which is remote from said trip arm, said actuating members being arranged on opposite sides of said cam, having their end portions curved about the same and terminating on opposite sides of and adjacent to said trip arm, and spring means to impart operative movement to said actuating members, said cam having its cam surfaces arranged to cause said actuating members to be successively released for operation by said spring means and then retracted.
17. In a mechanism of the character described, a pivoted support for a mercury tube switch having a trip arm to tilt the same, a cam mounted adjacent to said trip arm, actuating members pivotally mounted beyond that edge of said cam 25 which is remote from said trip arm, said actuating members being arranged on opposite sides of said cam, having their end portions curved about the same and terminating on opposite sides of and adjacent to said trip arm, and spring means to impart operative movement to said actuating members, said cam having two sets of cam surfaces arranged in different parallel planes to act on the respective actuating members.

ating members being arranged on opposite sides of said cam, having their end portions curved about the same and terminating on opposite sides of and adjacent to said trip arm, and spring means to impart operative movement to said actuating members, said cam having its cam surfaces arranged to cause said actuating members to be successively released for operation by said spring means and then retracted.

80

16. In a mechanism of the character described, a pivoted support for a mercury tube switch having a trip arm to tilt the same, a cam mounted adjacent to said trip arm, actuating members pivotally mounted beyond that edge of said cam which is remote from said trip arm, said actuating members being arranged on opposite sides of said cam, having their end portions curved about the same and terminating on opposite sides of and adjacent to said trip arm, and spring means to impart operative movement to said actuating members, said cam having two sets of cam surfaces arranged in different parallel planes to act on the respective actuating members.
